United States Patent Office.

JOEL GLEASON, OF WHITESTONE, NEW YORK.

Letters Patent No. 73,798, dated January 28, 1868.

IMPROVEMENT IN THE CONSTRUCTION OF SOLDERING-IRON.

The Schedule referred to in these Letters Patent and making part of the same.

TO ALL WHOM IT MAY CONCERN:

Be it known that I, JOEL GLEASON, of Whitestone, in the county of Queens, and State of New York, have invented a new and useful Improvement in Soldering-Tool; and I do hereby declare that the following is a full, clear, and exact description thereof, which will enable others skilled in the art to make and use the same, reference being had to the accompanying drawing, forming part of this specification.

The drawing represents a soldering-tool of my invention.

The design of this improvement is to make a solid soldering tool in two parts, and of the same or different metals, and consists in forming the copper point with a screw in the back end, which screws into a cast-iron base with a wrought-iron handle, or a base and handle of copper or any other suitable metal. With this plan of construction, the copper point admits of renewal when worn away so as to be too light for service, the handle part remaining as good as ever for a long time. In a tool of such extensive employment as the soldering-iron, this plan of construction will effect an important economy in the trade of plumbing and tinning, as the tools in common use have to be replaced by new tools when the points are worn away to render them too light for service.

In the drawing, A represents an independent copper point, having a screw, a, in the rear, which fastens the point to a cast-iron base or body, B, to give it proper weight for service, in which is cast a wrought-iron handle, C, the whole forming a soldering-tool similar in general conformation to the tool in common use, and always as effective as a new tool made entirely of copper. When the point A becomes worn, and the tool is too light for good service, it can be unscrewed from the cast-iron base B, and a new copper point put in its place at a trifling cost.

Having described my invention, I claim as new, and desire to secure by Letters Patent—

Constructing a soldering-tool formed of the copper point A, screwed into a cast-iron base, B, and provided with a wrought-iron handle, C, as and for the purpose herein described.

The above specification of my invention signed by me, this 6th day of March, 1867.

JOEL GLEASON.
